US00D511543S

(12) **United States Design Patent** (10) Patent No.: **US D511,543 S**
(45) Date of Patent: **** Nov. 15, 2005**

(54) **DATA CARD**

(75) Inventor: **Colleen C. Lubking**, Richmond, VA (US)

(73) Assignee: **Capital One Financial Corporation**, Falls Church, VA (US)

(**) Term: **14 Years**

(21) Appl. No.: **29/196,360**

(22) Filed: **Dec. 24, 2003**

Related U.S. Application Data

(62) Division of application No. 29/179,088, filed on Apr. 3, 2003.

(51) **LOC (8) Cl. 19-08**

(52) **U.S. Cl. D19/10**

(58) **Field of Search** D14/435, 436, D14/437, 438; D19/9, 10, 11, 12; D20/40; 235/380, 382, 435, 436, 449, 454, 468, 469, 488, 491, 492, 493; 283/70, 72, 74, 75, 82, 99, 107, 904; 360/2; 428/916

(57) **CLAIM**

The ornamental design for a data card, as shown and described.

DESCRIPTION

FIG. 1 illustrates a perspective view of a first embodiment of data card, showing my new design;

FIG. 2 illustrates a front plan view thereof;

FIG. 3 illustrates a rear plan view thereof;

FIG. 4 illustrates a bottom elevational view thereof;

FIG. 5 illustrates a top elevational view thereof;

FIG. 6 illustrates a left side elevational view thereof;

FIG. 7 illustrates a right side elevational view thereof;

FIG. 8 illustrates a front plan view similar to FIG. 2 but with a broken line illustration of an insert associated therewith;

FIG. 9 illustrates a perspective view of a second embodiment of data card, showing my new design;

FIG. 10 illustrates a front plan view thereof;

FIG. 11 illustrates a rear plan view thereof;

FIG. 12 illustrates a bottom elevational view thereof;

FIG. 13 illustrates a top elevational view thereof;

FIG. 14 illustrates a left side elevational view thereof;

FIG. 15 illustrates a right side elevational view thereof; and,

FIG. 16 illustrates a front plan view similar to FIG. 10 but with a broken line illustration of an insert associated therewith.

The broken lines in the figures have been shown for illustration purposes only and form no part of the claimed invention.
